FUEL INJECTION PUMP

Herbert C. Edwards, Massillon, Ohio, assignor to
 The Timken Roller Bearing Company, Canton,
 Ohio, a corporation of Ohio

Application August 2, 1940, Serial No. 349,532

6 Claims. (CL 103—41)

This invention relates to pumps, particularly single cylinder fuel injection pumps of the kind having a reciprocating plunger that is rotated in its cylinder to vary the quantity of fuel delivered. It has for its principal objects to provide a strong and durable smoothly operating light-weight pump of simple, economical and compact construction that can be quickly and easily assembled, adjusted and serviced and that will accurately meter the fuel charge. The invention consists in the construction, combinations and arrangements of parts hereinafter described and claimed.

In the accompanying drawings, which form part of this specification and wherein like symbols refer to like parts wherever they occur,

Fig. 1 is a plan view of a fuel injection pump embodying my invention,

Fig. 2 is a front elevational view of said pump,

Fig. 3 is a side elevation of the upper portion of said pump,

Fig. 4 is a view similar to Fig. 3 looking at the opposite side of the pump,

Fig. 5 is a central vertical section through the upper portion of the pump on the line 5—5 in Figs. 1 and 2,

Fig. 6 is a central vertical section on the line 6—6 in Fig. 1,

Fig. 7 is a horizontal section on the line 7—7 of Fig. 3,

Figs. 8, 9, 10, 11 and 12 are horizontal sections on the lines 8—8, 9—9, 10—10, 11—11 and 12—12, respectively, in Fig. 6,

Fig. 13 is a plan view of the plunger rotating sleeve,

Fig. 14 is a longitudinal section through said sleeve on the line 14—14 in Fig. 13,

Fig. 15 is an end view of the pinion for rotating said plunger rotating sleeve,

Fig. 16 is a central longitudinal section through 40 said pinion on the line 16—16 of Fig. 15,

Fig. 17 is a detail view, showing the manner in which the locking stud cooperated with the rack rod bushing; and

Fig. 18 is a plan view of the rack rod for rotating the pinion which rotates the plunger rotating sleeve.

In the accompanying drawings, my invention is shown in connection with a single cylinder fuel injection pump of the kind used for supplying measured charges of fuel to the cylinder of a compression ignition engine. Said pump comprises an upright cast metal housing 1 having a central vertical bore 2 extending therethrough from top to bottom thereof. Mounted in the bore

2 is a cylinder 3 having a head portion 4 seated on a gasket 5 resting on an annular seat 6 in said bore, and reciprocable in said cylinder is a plunger or piston 7.

5 Located in the bore 2 of the housing 1 is a tubular member 8 having a base flange 9 that seats on the upper end of the cylinder 3. This tubular member has a seat 10 at its upper end for a discharge valve 11. The valve seat member 8

10 fits loosely in the lower end of a tubular fitting 12; and said fitting is threaded into the upper end of the bore 2 of the housing 1 and thus serves to hold said valve seat member 8 down on the upper end of the cylinder 3 and said cylinder down on its seat in said bore. The fitting 12 also serves as a holder for a coil compression spring 13 that normally holds the discharge valve 11 down against the seat 10 provided therefor at the upper end of the valve seat member 8. A gasket 14 is interposed between the lower end of the fitting 12 and the base flange 9 of the valve seat member 8 to prevent leakage therebetween. The fitting 12 has its upper end threaded for connection with a fuel line (not shown) that leads to a fuel injector (not shown).

The bore 2 of the housing 1 has a substantially C-shaped groove 15 cast therein opposite the head 4 of the cylinder 3, said groove cooperating with said head of said cylinder to form a suction chamber 16 around the greater portion thereof. The housing 1 has a horizontal fuel inlet passageway 17 that opens into the C-shaped suction chamber 16 midway of the ends thereof; and the cylinder 3 has two radial, circumferentially spaced inlet and overflow ports 18 and 19, respectively, therein that establish communication between said opposite sides of said chamber and the plunger receiving bore of said cylinder.

30 Rotation of the plunger 7 in the bore 2 of the housing 1 is prevented by means of a screw 20 that is threaded into said housing and has a reduced inner end portion 21 that extends into the overflow port 19 which is enlarged, as at 22, to provide a clearance space for the passage of fuel around the inner end of said screw.

The plunger has an annular groove 23 therein near the upper end thereof that communicates through a longitudinal groove 24 with the pressure space 25 in the cylinder 3 and has an inclined or helical upper edge 26, whereby the delivery stroke of the plunger 7 may be regulated by turning said plunger to vary the point in the pressure stroke of said plunger in which the overflow port 19 is placed in communication with said 50 pressure space through the grooves 23 and 24 to

relieve the pressure in said space and thereby permit the delivery valve 11 to seat and terminate the fuel delivery. By this arrangement, delivery of fuel begins as soon as the plunger during its up-stroke covers the ports 18 and 19 and ends as soon as the helical edge 26 of the annular groove 23 in the plunger 1 opens the overflow port 18 and relieves the pressure in the space 25 above the plunger.

The mechanism for turning the plunger 1 on its axis to vary the amount of fuel delivered comprises a fuel control or feed rod 28, having teeth 28a intermeshing with a pinion 29 rotatable about the axis of the cylinder 3, and a sleeve 30 which is fixed to said plunger and extends upward around the cylinder 3 and has an axially slidable but non-rotary connection with said pinion. The lower end of the plunger rotating sleeve 30 has a non-rotary connection with the plunger 1 comprising a flat-sided portion 31 thereof that fits a similarly shaped opening 32 in the lower end of said sleeve. The axially slidable but non-rotatable connection between the upper end of the sleeve 30 and the pinion 29 comprises diametrically opposed upstanding fingers or tongues 33 at the upper end of said sleeve that have a sliding fit in diametrically opposed longitudinal grooves 34 in the pump cylinder receiving bore of said pinion.

Surrounding the driving sleeve 30 is a coil compression spring 35 that serves to retract the plunger 1 and hold the pinion 29 upwardly in the housing bore 2, whose lower end portion is enlarged, as at 36, to accommodate said pinion and said spring and to slidably support a tappet cup 37. The tappet cup 37, which is operated in one direction by a rotary cam or tappet (not shown), is spaced outwardly from the sleeve 30 so as to accommodate the retracting spring 35 for the plunger 1 and said tappet cup. A washer 38 supports the pinion 29 and is held against an annular shoulder 39 provided therefor in the bore 2 of the housing 1 by means of the piston retracting spring 35. The plunger 1 is provided below the bottom of the driving sleeve 30 with an annular groove 40 and terminates below said groove in a flatsided head portion 41. The lower end of the piston retracting spring 35 seats upon a C-washer 42 mounted on the plunger 1. The upper portion of the washer 42 receives the groove portion 14 of the plunger 1; and the lower portion of said washer is widened to receive the head 41 at the lower end of said plunger. The washer 42 seats on the bottom of the tappet cup 37 and is held against axial movement relative to the plunger but allows free rotation of the latter. The tappet cup 37 is retained in the bore of the pump housing by means of a snap ring 43 that seats in an annular groove formed in the wall of said bore adjacent to the lower end thereof.

With multi-cylinder engines, one of the above pumps is provided for each cylinder of the engine and the rack rods of the several pumps are linked together for simultaneous operation; and the links must be adjusted so that each pump will deliver the same quantity of fuel during simultaneous operation of the connected rack rods. It is, therefore, desirable to have some definite point marked on the rack rods so that the link connections therebetween can be quickly and easily adjusted. To facilitate such adjustment, the rack rod is supported in a bushing 43 mounted in a horizontal bore 44 in the housing 1, which bore opens into the vertical bore 2 of the pump

housing at one side of the pinion 29 therein; and one side of this bushing is cut away, as at 44a, to permit the rack teeth 28a of the rack rod 28 to intermesh with said pinion. The rack rod bushing 43 is inserted in and removable from the bore 44 from either end thereof and is rigidly clamped in said bore by means of a stud 45 that fits within a horizontal bore provided therefor in the housing 1 above the bushing supporting bore 44 and opens into the upper portion of the latter. The stud 45 has its underside notched, as at 46, to straddle the upper portion of the rack rod supporting bushing 43 and has its exposed outer end portion screwthreaded to receive a nut 47, the tightening of which exerts an end-wise pull on said stud thereby rigidly clamping the bushing 43 in said bore. The bushing 43 has its ends beveled, as at 48, and the rack rod 28 has a scale 49 marked thereon longitudinally thereof adapted to cooperate with one end of said bushing. The instructions for longitudinally adjusting the rack rod state that the fuel delivery of each pump should start at a specified distance from the zero mark on the scale 49, so that when the pump is tested and the start of injection in terms of rack position has been determined, the rack rod supporting bushing 43 is slipped lengthwise in its supporting bore 44 until such mark is in register with the end of said sleeve. The bushing 43 may then be clamped in the desired position of longitudinal adjustment by tightening the nut 47 on the stud 45.

The above described fuel injection pump has several important advantages. The plunger rotating sleeve 30 is rigidly fixed to the plunger 1 and is rotatably supported thereby. The cylinder 3 serves as a bearing for rotatably supporting the pinion 29. This pinion is positioned axially in the bore 2 of the housing between an annular shoulder therein and the upper spring seat 38 for the piston retracting spring 35. The longitudinal tongue-and-groove connections between the upper end of the sleeve 30 and the pinion 29 provide a simple and efficient axially slidable, nonrotary connection between said sleeve and said pinion which is simple and easy to manufacture and which requires a minimum amount of space axially of the pump. The C-shaped groove 15 in the bore of the pump housing may be cast in said housing and cooperates with the head 4 of the cylinder 3 to form the correspondingly shaped suction chamber 16. The suction chamber extends part way around the cylinder 3 and the inlet port 18 is on one side of said chamber, the overflow port 19 in the other side thereof and with the inlet passageway 17 opening into said chamber intermediate the ends thereof. This arrangement prevents the fuel by-passed into the suction chamber 16 through the overflow port 19 from interfering with the flow of the fuel from said chamber into the inlet port 18. The rack bar scale 49, which cooperates with the longitudinally adjustable rack rod supporting bushing 43, permits all pumps of a series to be set to have the same timing and metering characteristics; and it also makes it possible to shift the bushing to any new position should the pumps require readjusting after being reconditioned.

Obviously, numerous changes may be changed without departing from the spirit of my invention. Therefore, I do not wish to be limited to the precise arrangement shown and described.

What I claim is:

1. A fuel injection pump comprising a cylin-

der, a plunger reciprocable in said cylinder and projecting therebelow, a pinion rotatably mounted on said cylinder, and a sleeve fixed to said plunger below said cylinder and having an axially slidable but non-rotatable connection with said pinion, said connection comprising circumferentially spaced tongues on said sleeve that extend upwardly alongside said cylinder into the cylinder receiving bore of said pinion and are slidable in similarly spaced internal longitudinal 10 slideways in said cylinder receiving bore of said pinion.

2. A fuel injection pump comprising a cylinder, a plunger reciprocable in said cylinder and projecting therebelow, a pinion having an axial bore through which said cylinder extends, a sleeve fixed to said plunger below said cylinder and having a portion surrounding said cylinder and terminating at its upper end in upstanding circumferentially spaced tongues that extend into said bore of said pinion and have direct axially slidable but non-rotary connections with said bore, a spring seat mounted on said plunger below said sleeve, a spring seat mounted around said upstanding tongues of said sleeve and supporting said pinion, and a plunger actuating spring surrounding said sleeve and bearing against said spring seats.

3. A single cylinder fuel injection pump comprising a housing, a cylinder therein, a plunger reciprocable in said cylinder, said cylinder having a substantially C-shaped groove cast therein around said cylinder and cooperating therewith to form a similarly shaped suction chamber, an inlet passageway leading into said C-shaped suction chamber substantially midway of the ends thereof, and two circumferentially spaced ports in said cylinder disposed one on each side of said inlet passageway.

4. A fuel injection pump comprising a housing, a cylinder therein, a plunger reciprocable in said cylinder, a pinion rotatable about the axis of said cylinder, a member fixed to said plunger and having an axially slidable but non-rotary connection with said pinion, a bushing mounted in said housing at one side of said pinion transverse to the axis thereof for axial adjustment

5 relative to said housing, a rack rod reciprocable in said bushing and intermeshing with said pinion, and means for locking said bushing in said housing in the desired position of axial adjustment, said rod having a scale thereon extending longitudinally thereof and said bushing having an exposed index portion adapted to be brought into register with a certain graduation of said scale in a predetermined position of said rack rod by adjusting said bushing axially in said housing.

15 6. A fuel injection pump comprising a housing, a cylinder therein, a plunger reciprocable in said cylinder, a pinion rotatable about the axis of said cylinder, a member fixed to said plunger and having an axially slidable but nonrotary connection with said pinion, a bushing mounted in said housing at one side of said pinion transverse to the axis thereof for axial adjustment relative to 20 said housing, a rack rod reciprocable in said bushing and intermeshing with said pinion, and means for locking said bushing in said housing in the desired position of axial adjustment, said rod having a scale thereon extending longitudinally thereof and said bushing having an exposed index portion adapted to be brought into register with a certain graduation of said scale in a predetermined position of said rack rod by adjusting said bushing axially in said housing.

25 30 7. A fuel injection pump comprising a cylinder, a plunger reciprocable and rotatable in said cylinder and projecting therebelow, a pinion rotatably mounted on said cylinder, and a sleeve fixed to said plunger for rotary and axial sliding movement relative to said cylinder, said sleeve having a portion that extends upwardly between said cylinder and said pinion and has an axially slidable but nonrotary connection with said pinion entirely within the cylinder receiving bore thereof.

40 45 HERBERT C. EDWARDS.
